UNITED STATES PATENT OFFICE.

LAWRENCE E. JOHNSON, OF WINTHROP, MASSACHUSETTS, ASSIGNOR TO JULIUS GARST, OF WORCESTER, MASSACHUSETTS.

NAIL MAKING AND DRIVING MACHINE.

1,078,147.

Specification of Letters Patent. Patented Nov. 11, 1913.

Application filed November 8, 1912. Serial No. 730,488.

To all whom it may concern:

Be it known that I, LAWRENCE E. JOHNSON, a citizen of the United States of America, and a resident of Winthrop, in the 5 county of Suffolk and State of Massachusetts, have invented certain new and useful Improvements in Nail Making and Driving Machines, of which the following is a specification.

10 This invention relates to machines for making shoe nails and particularly to that class of machines in which the nail is formed from a continuous strip of flat wire intermittently fed to cutting devices which in 15 turn sever a blank from the wire and then remove from one edge of said blank a portion of the stock, thus forming a nail resembling a brad with a head projecting from one side of the body.

20 The main object of the present invention is to provide a means whereby various lengths of nails may be cut with their points of the same dimensions, provision being made whereby when the wire feeding mechanism is changed to give a different length 25 of nail, other devices controlled thereby will actuate the wire or blank being fed to move it into such position that when the cutting devices operate substantially the same 30 amount of stock will always be removed from its point end.

The invention consists primarily in means whereby the end of the blank or wire fed is always so positioned relative to the cutting mechanisms that substantially the same 35 amount of stock will be removed from its point end regardless of the length of the nail being formed.

The invention further consists in a back 40 stop provided with an inclined end against which the lower end of the blank or wire is adapted to be forced, prior to the operation of the cutting mechanism, by a pusher or slideable member the position of which is 45 regulated by the operation of the devices for controlling the length of wire to be fed.

The invention further consists in certain 50 novel features of construction and arrangement of parts which will be fully understood by reference to the description of the drawings and to the claims hereinafter given.

Of the drawings: Figure 1 represents an 55 elevation of the front end of a machine embodying the features of the present in-

vention. Fig. 2 represents a left side elevation of a portion of the same. Fig. 3 represents a vertical section of a portion of the same, the cutting plane being on line 3—3 on Fig. 2. Fig. 4 represents a horizontal section of a portion of the same, the cutting plane being on line 4—4 on Fig. 1, said view being drawn to an enlarged scale. Fig. 5 represents a similar view to Fig. 4, showing the position of the parts after the 60 nail has been formed and moved into position to be driven. Fig. 6 represents a vertical section of the same, the cutting plane being on line 6—6 on Fig. 4. Fig. 7 represents a similar view to Fig. 6, showing the 65 position of the end of the wire when fed for a short length of nail. Fig. 8 represents a similar view showing the position of the pusher when a full length of nail is to be formed. Fig. 9 represents a right side elevation of a portion of the machine supporting the stationary knife, the back stop, and the driver guide. Fig. 10 represents an elevation of the mechanism for controlling the 70 length of wire to be fed, and Fig. 11 represents a plurality of nails of various lengths adapted to be formed in said machine, all of 75 said nails having the same sized heads and substantially the same sized points.

Similar characters designate like parts 80 throughout the several figures of the drawings.

In the drawings, 10 represents a column having secured to its upper end a head 11, 85 said head being of any suitable shape to support the working parts. In the head 11 is mounted a revoluble shaft 12, driven in any suitable manner. To the front end of the shaft 12 is secured the driver lifting cam 13, adapted to act upon a collar 14 fixed on the driver bar 15, the lower end of which is provided with a driver 16. The cam 13 is adapted to lift the bar 15, while a suitable spring 17, acting upon a lever 18, is provided to depress said bar. The shaft 12 has also secured thereto the disk 19 having in its front face a cam groove 20 and in its rear face another cam groove not shown. In the cam groove 20 is positioned a roller mounted upon a stud 21 of a lever 22 pivoted at 23, the lower end of said lever being provided with a segmental rack 24, the teeth of which engage the teeth of the pinion 25 secured to a short shaft 26 having at its outer end a pawl carrying arm 27. 100 105 110

This arm 27 has pivoted thereto a pawl 28 acted upon by a spring 29 to normally retain it in engagement with the teeth of the ratchet wheel 30. The pawl 28 has a constant throw and would consequently always have a definite stroke, thereby moving the strip feeding wheel 31 a definite distance and causing it to act against one edge of the strip 32 to feed it always for a like distance. In such case the nails would all be of a certain length. In order, however, to vary the length of the nails this pawl has combined with it a shield 33 as shown in Fig. 3 attached by screws to the length adjusting lever 34 having a fulcrum on the shaft 26 alongside the ratchet wheel 30. It is obvious that by moving this lever 34 the shield may be interposed between the ratchet wheel 30 and the pawl 28 so that the effective stroke of the pawl 28 in moving the ratchet wheel may be altered as desired to cause the strip to be fed for a greater or less distance according to the length of nail desired. This lever 34 is moved by hand and has a spring actuated locking pin 35 which co-operates with a toothed segment 36 secured to the machine head 11, the locking pin holding the lever 34 in adjusted position.

The periphery of the disk 19 is provided with ratchet teeth 37 which are engaged by a pawl 38 to prevent the shaft 12 from turning backward. The strip 32 is taken from a reel 39 suitably mounted on the machine, and is led through a suitable guide 40 and then between the feed roll 31 and a co-operating roll 41 mounted on a stud carried by a lever 42 pivoted at 43. The opposite end of said lever 42 is provided with a pressure adjusting device shown as a screw 44 whereby the pressure or force with which the strip is grasped may be varied. After passing below the feed wheels 31, 41, the strip 32 enters a guideway 45, said guideway being made of a steel block having its lower end hardened.

The machine is provided with a vertical bearing for the shank 46 of an oscillating lever 47 provided at its inner side near its outer end with a steel block 48 having a vertical peripheral groove 49 adapted to receive a portion of the strip 32 when fed thereto. The groove 49 extends through a lip 50 extending outwardly from the periphery of said block 48, said lip conforming in cross section to the shape of the head desired for the nails to be formed.

When the lever 47 is moved about the axis of the shank 46 thereof the upper surface of the block 48 will travel beneath and in close proximity to the hardened end of the guide 45, acting therewith to cut the strip transversely into nail lengths or blanks. The lever 47 has upon it a loose block 51 retained in place by a collar 52, said loose

block being embraced by a forked block 53 having a shank 54 which is entered loosely in a hole in the lower end of the lever 55 pivoted at 56 and having a roller or other stud 57 which enters the cam groove in the back of the disk 19, said cam groove being shown only in dotted lines in Fig. 2 of the drawings. The loose fork enables the two levers 55 and 47, one in a vertical and the other in a horizontal plane, to work freely. The head 11 of the machine has secured thereto a tubular nose 58 held in position by means of the set screw 59, as indicated in Fig. 1 of the drawings.

When the machine is in operation the nail formed is driven by the driver 16 into the work through this tubular nose 58, the nose resting upon the work presented thereto by the hand of the operator. The tubular nose 58 is partially embedded in the plate 60 secured by means of the screws 61 to the projection 62 forming a part of the head of the machine. Above the said plate 60 this projection has an inclined slot formed therein in which is placed side by side a back stop 63, a fixed knife or cutter 64, and a driver guide 65. These members, 63, 64, and 65, are held in adjusted positions by means of the screws 66 threaded to the projection 62. When the strip 32 has been fed through the guide 45 a sufficient distance into the groove 49 the lever 47 will be moved causing the strip to be cut off between the upper side of the lip 50 and the lower hardened end of the guideway 45. The blank thus formed and positioned within the slot 49 is borne against the fixed knife 64, thereby causing a portion of the stock to be cut from one edge of this blank, and in doing so leaving a head 95 the full width of the strip and of a depth equal to the depth of the lip 50. The nail having been thus formed the lever 47 continues its movement in the direction in which it started until the peripheral groove 100 49 arrives opposite the driving groove 67 formed in the steel block 68 held in fixed position opposite to the outer peripheral face of the block or die 48. The block 48 is secured to the lever 47 by means of the 105 screw 69 and constitutes a movable cutter member which co-operates with the fixed knife or cutter member 64.

The machine as thus far described is substantially the same as that shown and described in Letters Patent No. 562,597 issued June 23, 1896 to J. B. Flint and A. J. Howard, and to which reference may be made for any details of construction not clearly shown in the drawings forming part of 115 this application.

It is obvious that in the machine hereinbefore described nails of various lengths may be formed, but the shorter nails would have thicker points than the longer nails 120 130

and would be so blunt that it would be very difficult to drive and clinch them. This is very objectionable and it is desirable that all the nails formed in the machine regardless of length should have their points of substantially the same dimension. In order to obtain this result the distance between the inner end of the bottom of the back stop 63 and the inner wall of the groove or slot 49 is equal to the width of the strip 32, while the distance between the upper part of the inner wall of the groove or slot 49 and the end 70 of the back stop 63 is greater. By this means if the strip 32 is fed sufficiently to form a full length nail the lower end thereof when fed will contact at one edge with the entire inner wall of the groove 49 while its opposite edge will contact with the extreme lower portion of the inclined wall 70. Should the lever 47 be operated when the strip 32 has been fed into the peripheral groove 49 a distance equal to the length of the longest nail, a nail will be formed similar to that shown at *a* in Fig. 11 of the drawings. Should the strip 32 be fed for any shorter length of nail it is necessary in order to secure the same dimension of point thereto that the lower extremity of the wire or strip thus fed should be forced against the inclined walls 70 of the back stop 63 before the cutting devices operate.

In Fig. 7 of the drawings is shown the strip 32 fed into the peripheral groove 49 a distance sufficient to form the shortest length of nail, as for instance the nail *b* shown in Fig. 11 of the drawings. It is evident that in order to form this nail it is necessary that the portion of the strip 32 fed below the guide 45 should be bent to the right as indicated in said Fig. 7 until its lower extremity contacts with the inclined wall 70, and some means must be provided to retain this bent portion in contact with the back stop 63 until the cutting operation takes place. The means provided for forcing the fed portion of the strip 32 against the inclined wall 70 is the slidable member or pusher 71, this slidable member being positioned in a groove in the under side of the lever 47 and held in position therein by means of the plate 72 secured to the under face of said lever. This slidable member 71 is provided at its inner end with a thin extension 73 of the same width as the width of the groove 49. This extension 73 is normally positioned in the groove 74 cut transversely of the steel block 48 forming the movable cutting member, said groove 74 communicating with the peripheral groove 49 in the same plane therewith. The extreme end of this extension 73 is downwardly inclined as at 75, so that as the strip 32 is fed from the guide 45 its end will strike the inclined end 75 when the slidable member 71

has been moved from its normal position to the right as indicated in said Fig. 7. As the strip 32 continues to be fed downwardly, it is obvious that its extreme lower end will be forced into contact with the inner end 70 of the back stop 63. This pusher or slidable member 71 and its extension 73 are held normally in the position shown in Fig. 8 of the drawings by means of the spring 76 which forces said member 71 into contact with the inner wall of the lever 77 pivoted at 78 and provided at its upper end with the roller 79 held in contact with the face of the cam member 80 by means of said spring 76. This cam member 80 is a part of the lever 34 carrying the shield 33 regulating the stroke of the pawl 28. The face of the cam member 80 is so formed that it will move, through the lever 77, the slidable member 71 a sufficient distance to force the strip 32 into contact with the inner wall 70 of the back stop 63 for any given length of nail. In other words, when the full length nail is to be formed no movement of the slidable member 71 is necessary, but for any shorter length of nail it is necessary that the slidable member 71 should be moved toward the back stop a predetermined distance, dependent upon the length of nail to be formed, that is, the shorter the nail to be formed the greater the distance it is necessary to move the slidable member 71. When the lever 47 is in its normal position the slidable member 71 is in alignment with the inclined end 70 of the back stop 63, as indicated clearly in Fig. 4 of the drawings. When in this position the strip 32 is fed into the peripheral groove 49 and when a sufficient length of the strip has been fed thereto the lever 47 will be moved in the direction of the arrow *c*, thereby severing a blank of the required length from the strip 32. The continuation of the movement in this direction will cause this blank to be carried into contact with the fixed cutting knife 64 and a portion of the stock will be cut away from one edge of the blank as the movable member 48 passes by the shearing knife edge of the member 64. Further movement of the lever 47 in the same direction carries the nail thus formed into a position opposite the groove 67 and beneath the driving member 16. The driving member is then free to be operated in the usual manner to drive the nail through the nose piece 58 into the stock to be nailed.

For convenience the lever 34 is provided with an opening 81 therethrough, through which the graduated scale 82 may be seen to assist in registering the position of said lever 34 and thereby determine the size of the nail to be used. It is obvious that when the lever 34 is moved into position for a given size of nail as indicated on said scale 82, the shield 33 will be moved into a position to give a certain stroke and cause a constant

- feeding of the strip 32 until the position of the lever 34 has been again changed for another length of nail. The same movement of the lever 34 will cause the cam member 80 to operate the slidable member 71 and move it the required distance for the length of nail determined by the position of the lever 34. The locking member 35 will then retain the lever 34 and all of the parts actuated thereby in adjusted position. When the lever 34 has been once adjusted and locked in position the machine will continue to operate to form nails of the predetermined length until the lever is shifted for another length. The lever 77 is provided with a lug 83 extending rearwardly from its lower end, said lug having a cam face 84 against which bears the end of the slidable pusher member 71. This cam face 84 is so formed that when the lever 47 is moved about its axis to carry the blank severed from the wire 32 into a position beneath the driver 16 the slidable member 71 will be moved outwardly by means of the spring 76 out of the path of said driver to permit it to drive the nail when formed. On the reverse movement of the lever 47 the cam surface 84 will act upon the member 71 to return it to the position in which it was originally adjusted.
- 30 By means of a machine constructed as herein described nails of various lengths may be formed from a strip of stock and each length of nail will have a point suitable for ready insertion into the work being operated upon and adapted to be readily clenched therein.
- 35 It is believed that the operation and many advantages of the invention will be thoroughly understood from the foregoing description.
- 40 Having thus described my invention, I claim:
1. In a machine of the class described, the combination of wire feeding mechanism; slabbing mechanism for removing stock from one side of the wire fed, manually controlled means for severing from said wire nails of different lengths; and manually operated means for varying the position of the wire relative to said slabbing mechanism so that the points of all the nails cut thereby will correspond.
  2. In a machine of the class described, the combination of a slabbing mechanism for removing stock from one side of a wire; mechanism for feeding wire to said slabbing mechanism; and manually controlled means for inclining the wire thus fed prior to the slabbing operation.
  3. In a machine of the class described, the combination of a slabbing mechanism for removing stock from one side of a wire; mechanism adapted to be adjusted to feed predetermined lengths of wire to said slabbing mechanism; and manually controlled

means for insuring the removal of the same amount of stock from the extreme end of said wire for all lengths of nail.

4. In a machine of the class described, the combination of wire feeding mechanism; means for inclining the end of said wire; and means for cutting stock from one side of the inclined portion and severing a length from said wire to form a headed nail. 70

5. In a machine of the class described, the combination of wire feeding mechanism; manually controlled means for varying the inclination of the end of said wire for various lengths of nails; and means for cutting stock from one side of the inclined portion 80 and simultaneously severing a length from said wire to form a headed nail. 75

6. In a machine of the class described, the combination of wire feeding mechanism; an oscillating member movable transversely of 85 the direction of feed of said wire and provided with a slot adapted to receive a portion of said wire; a fixed knife coacting with said oscillating member; and a slidable member in said slot adapted to vary 90 the position of the end of wire positioned in said slot.

7. In a machine of the class described, the combination of wire feeding mechanism; an oscillating member movable transversely of 95 the direction of feed of said wire and provided with a slot adapted to receive a portion of said wire; a fixed knife coacting with said oscillating member; a slidable member in said slot adapted to vary the position of the end of wire positioned in said slot; and means for varying the position of said slidable member in said slot. 100

8. In a machine of the class described, the combination of wire feeding mechanism; an oscillating member movable transversely of 105 the direction of feed of said wire and provided with a slot adapted to receive a portion of said wire; a fixed knife coacting with said oscillating member; and a slidable member in said slot provided with a downwardly inclined operating end adapted to be moved into the path of said wire as fed. 110

9. In a machine of the class described, the combination of wire feeding mechanism; an oscillating member movable transversely of 115 the direction of feed of said wire and provided with a slot adapted to receive a portion of said wire; a fixed knife coacting with said oscillating member; mechanism 120 for controlling the amount of feed of said wire; a slidable member in said slot adapted to vary the position of the end of wire positioned in said slot; and means operable by said controlling mechanism for varying the 125 position of said slidable member in said slot.

10. In a machine of the class described, the combination of wire feeding mechanism; mechanism for cutting nails from the wire as fed, said mechanism consisting in part of 130

an oscillating member; a back stop in the same plane with said wire; and a slidable member carried by said oscillating member for forcing the end of said wire against said back stop prior to the operation of the cutting mechanism.

11. In a machine of the class described, the combination of wire feeding mechanism; mechanism for cutting away stock from one edge of the wire and separating a length from said wire, said mechanism consisting in part of a movable member; a back stop having an inclined end; and means carried by said movable member for forcing the end of the wire against said back stop prior to the cutting operation.

12. In a machine of the class described, the combination of wire feeding mechanism; cutting mechanism to which the wire is adapted to be fed adapted to remove an elongated section of stock from one side of the wire; and manually operated means for adjusting said feeding mechanism to feed a predetermined length of wire so that various lengths of nails may be cut with the same shaped points without altering said cutting mechanism.

13. In a machine of the class described, the combination of wire feeding mechanism; an oscillating member movable transversely of the direction of feed of said wire and provided with a slot adapted to receive a portion of said wire; a fixed knife coacting with said oscillating member; a back stop; and a slidable member in said slot adapted to force the end of wire positioned in said slot against said back stop.

14. In a machine of the class described, the combination of wire feeding mechanism; an oscillating member movable transversely of the direction of feed of said wire and provided with a slot adapted to receive a portion of said wire; a fixed knife coacting with said oscillating member; a back stop normally in the same plane with said slot; a movable member in said slot adapted to vary the position of the end of wire positioned in said slot; and means for moving said member in said slot and forcing the end of the wire against said back stop.

15. In a machine of the class described, the combination of wire feeding mechanism; an oscillating member movable transversely of the direction of feed of said wire and provided with a slot adapted to receive a portion of said wire; a fixed knife coacting with said oscillating member; a back stop; and a slidable member in said slot provided with a downwardly inclined operating end adapted to be moved into the path of the end of the wire as fed thereby forcing it against said back stop.

16. In a machine of the class described, the combination of wire feeding mechanism; an oscillating member movable transversely

of the direction of feed of said wire and provided with a slot adapted to receive a portion of said wire; a fixed knife coacting with said oscillating member; mechanism for controlling the amount of feed of said wire; a back stop; a slidable member in said slot adapted to be moved to force the wire as fed against said back stop; and means operable by said controlling mechanism for varying the position of said slidable member in said slot.

17. In a machine of the class described, the combination of a fixed cutting member; a movable cutting member provided with a slot to receive wire stock; a back stop; a pusher carried by said movable cutting member adapted to force the lower end of the stock against said back stop; and means for moving said movable member into position to coact with said fixed cutting member and thereby form a nail from said stock.

18. In a machine of the class described, the combination of a fixed cutting member; a movable cutting member provided with a slot to receive wire stock; a back stop; a slidable member having an inclined end; and means for operating said slidable member to cause said inclined end to enter said slot in the path of said stock thereby forcing its lower end into contact with said back stop.

19. In a machine of the class described, the combination of a fixed cutting member; a movable cutting member provided with a slot to receive wire stock; a back stop having its inner face inclined with its lower end distant from the bottom of said slot the width of said stock; a slidable member having an inclined end; and means for operating said slidable member to cause said inclined end to enter said slot in the path of said stock thereby forcing its lower end into contact with the inclined edge of said back stop.

20. In a machine of the class described, the combination of a wire feeding mechanism; devices for severing and slabbing said wire; a back stop having an inclined operating end; a slidable member adapted to force the wire as fed against said inclined end; a device for regulating the operation of said feeding mechanism; a cam operable thereby; and means interposed between said cam and said slidable member whereby a predetermined feed of the wire will impart a desired movement to said slidable member.

21. In a machine of the class described, the combination of a wire feeding mechanism; devices for severing and slabbing said wire; a back stop having an inclined operating end; a slidable member adapted to force the wire as fed against said inclined end; a device for regulating the operation of said feeding mechanism; a cam operable thereby; and a pivoted lever provided at one end with a cam contacting member and at the

other end with a surface contacting with the end of said slidable member.

22. In a machine of the class described, the combination of a wire feeding mechanism; devices for severing and slabbing said wire; a back stop having an inclined operating end; a slidable member adapted to force the wire as fed against said inclined end; a spring for normally retaining said slidable member out of the path of said wire; a device for regulating the operation of said feeding mechanism; a cam operable thereby; and a pivoted lever provided at one end with a cam contacting member and at the other end with a surface contacting with the end of said slidable member.

23. In a machine of the class described, the combination of a wire feeding mechanism; devices for severing and slabbing said wire; a back stop having an inclined operating end; a slidable member adapted to force the wire as fed against said inclined end; a spring for normally retaining said slidable member out of the path of said wire; a device for regulating the operation of said feeding mechanism; a cam operable thereby; and a pivoted lever provided at one end with a cam contacting member and at the other end with an inclined surface contacting with the end of said slidable member.

24. In a machine of the class described, the combination of a wire feeding mechanism; a fixed knife; an oscillating member coacting therewith provided with a slot adapted to receive the wire as fed; a back stop opposite said slot having the top of its inner end a greater distance from the inner wall of said slot than its lower end; and means controlled by the wire feeding mechanism for retaining the end of the wire fed in contact with said inner end preparatory to the movement of said oscillating member to form a nail.

25. In a machine of the class described, the combination of a wire feeding mechanism; a fixed knife; an oscillating member coacting therewith provided with a slot adapted to receive the wire as fed; a back stop opposite said slot having the top of its inner end a greater distance from the inner wall of said slot than its lower end; means controlled by the wire feeding mechanism for retaining the end of the wire fed in contact with said inner end preparatory to the movement of said oscillating member to form a nail; and a driving member posi-

tioned above the slot in said oscillating member when at the end of its movement after its slabbing operation has been completed.

26. In a machine of the class described, the combination of wire feeding mechanism; severing and slabbing cutters to which the wire is fed; a device for positioning the wire during the cutting operation; a driver; mechanism for moving the formed nail beneath the driver; and means for withdrawing the positioning device from the path of said driver prior to the operation of the latter.

27. In a machine of the class described, the combination of wire feeding mechanism; severing and slabbing cutters to which said wire is fed; a slidable member adapted to be moved against one edge of said wire and position it during the cutting operation; a driver; mechanism for moving the formed nail beneath the driver; and means for withdrawing said positioning member from the path of said driver prior to the operation of the latter.

28. In a machine of the class described, the combination of wire feeding mechanism; severing and slabbing cutters to which said wire is fed; a slidable member adapted to be moved against one edge of said wire and position it during the cutting operation; a driver; mechanism for moving the formed nail beneath the driver; and a spring for withdrawing said positioning member from the path of said driver prior to the operation of the latter.

29. In a machine of the class described, the combination of wire feeding mechanism; severing and slabbing cutters to which said wire is fed; a slidable member adapted to be moved against one edge of said wire and position it during the cutting operation; a driver; mechanism for moving the formed nail beneath the driver; means for withdrawing said positioning member from the path of said driver prior to the operation of the latter; and a lever adapted to be forced against said slidable member provided with a cam surface limiting the outward movement of said slidable member.

Signed by me at 4 Post Office Sq., Boston, Mass., this 21st day of October, 1912.

LAWRENCE E. JOHNSON.
